[57] CLAIM

The ornamental design for an oil change device, as shown and described.

DESCRIPTION

FIG. 1 is an exploded perspective view of the oil change device showing my new design shown in a flexed condition; FIG. 2 is an exploded front elevational view thereof, the rear elevational view, left side elevational view and right side elevational view, all in exploded form, being identical to the view shown in this Figure;

FIG. 3 is a top plan view thereof;

FIG. 4 is a bottom plan view thereof; and,

FIG. 5 is an assembled front elevational view thereof, the rear elevational view, left side elevational view and right side elevational view, all in assembled form, being identical to the view shown in the Figure;

1 Claim, 2 Drawing Sheets

FIG.2.

FIG.5.

FIG.3.

FIG.4.
